Application February 2, 1937, Serial No. 123,684

22 Claims. (Cl. 92—29)

This invention relates to a method and apparatus for classifying or separating fiber particles according to size. It more particularly relates to the classifying or separating of fiber particles which have appreciable length as compared to width or breadth and is particularly adapted to the screening of wood pulp fibers used for paper making.

Such fibers in their ideal condition are long, and relatively thin particles. For this reason, a screen opening must be provided which has considerably greater length than width in order that these long, thin fibers may pass through the screen openings and large fibers or groups of fibers which may be attached to each other, in which condition they are not suitable for use, can be separated from those thinner or individual fibers which are satisfactory.

The method hereinafter described is so arranged and its method of operation so determined that the fibers are brought into relation with the screen surface with their maximum length or dimension coinciding with the lengthwise direction of the slotted opening in the classifying screen.

This arrangement of fibers is obtained without the use of mechanical agitators or rotating members for creating turbulence or circulation. All parts of the screening surface are submerged below the level of the liquid eliminating air in either the screened or unscreened material, which air interferes with efficient classification and contributes to difficulties when the fibers are felted on a paper machine.

A uniform pressure head on all parts of the screen surface is maintained making for maximum capacity and efficiency. This pressure head can be adjusted as may be necessary or desirable for different materials and operating conditions. There are no moving or rubbing parts requiring lubrication which are in contact with the pulp mixture. The absence of rubbing or friction parts and the mechanical agitators, stirrers or other circulating means results in extremely low power operating requirements for screen operation.

The apparatus is illustrated by the following drawings.

Fig. 1 is a vertical sectional elevation through the apparatus on line 1—1 of Fig. 2.

Fig. 2 is a plan view of the apparatus, a portion of which is shown in section through line 2—2 of Fig. 1.

Fig. 3 is an end elevation on line 3—3 of Fig. 2 showing the method by which the lever arm is supported.

Fig. 4 is a sectional view through overflow box for rejected fibers.

Fig. 5 is a fragmentary view of a portion of the screening surface.

Fig. 6 is a diagrammatic view illustrating the method of operation by which the fibers either pass through or are rejected by the screening surface.

Fig. 7 is a diagrammatic view illustrating the segregation or separation of fibers of different size and weight.

Fig. 8 is a diagrammatic view illustrating the method by which the smaller fibers are disengaged or disentangled from amongst the larger fibers and the means by which these disengaged fibers are brought into contact with the screen surface.

The apparatus consists of a base 1, on which is mounted the screening tank 2, the lever mounting bracket 3, and the eccentric shaft bearing 4. Screen tank 2 is generally cylindrical in shape and is supported from the base 1 supporting legs 5.

The fibers to be screened are mixed with water or other similar medium and enter the tank 2 through nozzle 6, which nozzle is mounted tangentially on tank 2 near the bottom. On one side of the tank near the top is an overflow box 7, which box has an adjustable weir or gate 8 by means of which the height or level of the fibers and water in the tank can be regulated.

Mounted on one side of the tank 2 and extending for a considerable portion of its height is a chamber 9 having connected thereto a plurality of spray nozzles 10. Water under pressure is supplied to chamber 9 through pipe 11.

Mounted inside the circular tank 2 is the screen proper. This consists of the screen itself 12 having elongated perforations 13 located therein as illustrated in Figure 5. This screen member 12 is supported on a bottom flange 14 which in turn is fixed and secured to a tube or hollow member 15. The screen 12 is held in place on member 14 by an upper member 16 and clamp nut 17.

With the tank 2 empty the screen 12 itself can be readily removed for inspection by loosening and removing the clamp nut 17, lifting the upper member 16 from the screen and then lifting the entire screen 12 out of the tank. It can be re-installed with equal facility after inspection.

The hollow member or tube 15 which supports the lower screen supporting member 14 is carried by a lever arm 18 being clamped therein by means of a split end 19 in said arm and clamp

bolts 20. The lever arm 18 is in turn carried by a swinging link 21 being pivotally connected thereto by means of a lever bearing pin 22 which forms two pivot bearings 23a and 23b, these being located above and below lever 18 respectively.

The opposite end of the link 21 is pivotally mounted to a bracket 3 by means of a bearing pin 24 which forms two bearings 25a and 25b located at the upper part and lower part respectively of link 21. The bracket 3 is fixed to the base plate 1 by means of bolts 26.

The opposite end of the lever arm 18 is provided with a bearing 27 which bearing in turn is mounted on an eccentric 28. This eccentric 15 28 is fixed to a shaft 29 which shaft in turn is carried by a bearing 4 and bushing 30. This shaft is held in place vertically by means of an integral upper collar 31 on the shaft and an adjustable collar 32 on the lower end of the shaft. The shaft may be rotated or driven by any convenient means such as a belt pulley 33.

When the shaft 29 is rotated in the direction of the arrow, the end of the lever 18 describes a small circle or moves in a circular path depending on the amount of eccentricity or throw of the eccentric 28. With the eccentric end of the lever 18 moving in a circular path, the center portion of the lever 18 at 34 is moved back and forth substantially endwise, the point 34 swinging about the point 35 by means of the link 21 previously described.

The opposite end of the lever 18 to the eccentric 28 is also moved in a circular path similar in magnitude to that imparted to the eccentric end of the lever but in the opposite direction as is indicated by the small arrow in the center of the hollow tube 15. The hollow tube 15 moved in a circular direction by the lever 18 of course carries with it the screen supporting and clamping member 14 and 16 and the screen 12 itself.

The link 21 not only permits a swinging motion about the point 35 enabling the lever arm 18 to move endwise but also permits it to swing endwise about the fulcrum point 34. The link 21 45 has the further purpose of firmly supporting the lever 18, the hollow tube 15, the screen 12 and associated parts. While firmly supporting lever and screen, the link 21 permits easy and ready movement of the screen in a small circle as heretofore described under the urge and control of the eccentric 28 on the shaft 29.

As tank 2 contains a mixture of fibers and water or other liquid, it is necessary to provide a seal between the moving screen or its bottom supporting member 14 and the bottom of the tank 2. This is accomplished by means of a rubber seal ring 36 secured to the bottom of member 14 by means of a clamp ring 37. The lower end of the rubber ring 36 is secured in a loose ring 38 which ring is clamped tightly to the inside of the tank 2 by means of clamp members 39.

The purpose of this construction is to provide a flexible, durable and watertight seal between 65 the moving part 14 and the stationary part 2 and also to provide means by which the hollow tube 15 together with the rubber sealing ring 36 and associated parts can be removed from tank 2 for inspection. This is readily accomplished by loosening the clamp bolts 20 in the end of the lever 18 and removing clamp members 19. The entire tube and other parts including the rubber ring 36 and its clamp and sealing rings 75

37 and 38 can then be vertically removed from the tank and be as readily replaced.

Located on one side of the tank near the top is an overflow box 7 in which is located a weir or gate 8. This weir or gate may be changed as to height which in turn will change the upper level 40 of the fibers and water in the tank 2. When the mixture in the tank 2 reaches the top of the gate 8 it can overflow passing off through pipe 41.

It will be noted that the feed nozzle 6 is located practically at the bottom of the tank and when it is desired to empty the tank 2 for inspection or cleaning the pulp mixture therein can be drained back through the feed nozzle. If desired of course a drain valve can be provided in the bottom of tank 2.

In order to drain the inside of the screen itself, a valve 52 is provided inside the hollow tube 15. This valve consists of a sleeve which can be moved upward inside the tube normally resting on a seat 53.

Just above seat 53 are located holes 54 through the screen supporting member 14 and through tube 15, these holes being located at the extreme bottom of the inside of the screen chamber. Normally valve 52 resting on the seat 53 closes holes 54 and prevents escape of the water and fibers contained inside the screen requiring them to normally overflow through holes 44 near the top of tube 15. When it is desired to empty or drain the chamber inside the screen, the cap 17 at the upper end of tube 15 is removed and the valve 52 pulled upward by means of rod 55. The top of this rod when the valve is closed is located just below the inside top of cap 17 to insure that valve 52 is always closed when cap 17 is in place, and the screen about to be used.

In order to prevent any tendency of the screened material from effecting a syphoning action while flowing downward through tube 15 an air vent opening is provided in the top of cap 17, consisting of a short pipe or tube 56 connecting to the interior of the cap and the top opening of the tube extending above the top of tank 2 to prevent unscreened fibers from reaching the interior of the screen or tube 15.

Referring more particularly to Figs. 6, 7 and 8 I will now describe the method by which the apparatus previously illustrated and described operates.

Considering first Figure 7. It has already been stated that the mixture of fibers and water which are to be screened are introduced near the bottom of the tank through nozzle 6. The location of this nozzle is such that the flow of water and fibers into the tank 2 imparts to them a natural rotary motion around the walls of tank 2 and around the screen 12 located within said walls. This rotary motion of the fibers and water is a natural one, and is accomplished without the use of propellers, agitators or other mechanical means which would disturb the flow of the mixture of the fibers and water about the screen 12. This flow introduced through nozzle 6 naturally spirals or climbs upward as it passes around and around the tank and eventually if there were no openings in the screen surface 12 all of the mixture introduced through the nozzle would gradually spiral upward passing around the tank several times until it reached the top of the overflow gate 8 when it would overflow from the tank 2 and out through pipe 41.

This natural circulation of the fibers and water around the inner surface or wall of tank 2 causes

a natural segregation or separation of fiber particles according to weight and in general according to size. This is indicated in Fig. 7 with the larger and heavier fiber particles shown at 42 and the smaller and lighter fiber particles at 43. In Fig. 7 there is shown the outer wall of tank 2 and inside of this the screen 12 with its slotted or elongated openings 13.

It will be readily understood that the heavier and larger fiber particles will gravitate outwardly and towards tank walls 2, leaving smaller and finer fiber particles nearer the screen surface. This action is not however, to be construed as effecting a complete separation or segregation of the fiber particles according to size.

It has already been stated that the fibers in the pulp mixture to be screened are in general long, thin, particles particularly those which are useful, these being indicated by the numeral 43. Mixed with these are larger and coarser particles indicated at 42, which are not suitable for use and which must be separated from the thinner fibers.

It has already been described that in order to effect proper separation of the larger and smaller particles it is necessary to pass these through a relatively narrow opening as the important element in satisfactory screening is the measurement of particle width rather than length.

In order to effect such a separation and secure maximum screen capacity it is necessary that the fiber particles be aligned or arranged parallel to the slot openings 13 in the screen 12 in order that their width may be determined and if less than the width of the slot 13 that they may pass through the screen and that if greater than the width of slot 13 that they may be rejected by the screen and prevented from passing through.

On the other hand if a fiber particle of satisfactory width approaches the screen crosswise or at an angle to slots 13 it cannot reasonably be expected to pass through the slot even though the fiber size is satisfactory. If the fiber had been properly aligned with the slot it would have passed through.

It is a well known fact that logs floating down a stream or river will normally, if the flow of the stream or river is uniform, assume a path or direction lengthwise of the stream. This is due primarily to two causes.

First, the center of the stream is usually flowing slightly faster than other portions, hence if one end of the log extends over near the shore where the water is moving slower than at the center of the stream, the motion of this end of the log is retarded tending to straighten the log out in the direction of stream flow.

Second, because the logs may actually touch or contact the bottom of the stream bed or its banks holding one end of the log back allowing the other end to go ahead, thus further effecting a straightening out or paralleling the log length with the general direction of stream flow.

Such a condition is however only true where the stream flow is smooth and lacks undue turbulence. Where the stream flow is broken up by obstructions and is turbulent, flowing in eddies, circles and cross currents the log no longer assumes or aligns its length with general direction of stream flow, but swings and turns as affected or influenced by the turbulence and cross currents in the stream itself.

The fibers under consideration are in effect small diameter particles of wood, and can be

aligned with stream flow direction in exactly the same manner as the logs previously described and from whence these fibers were made. However, to accomplish this, the stream flow must lack turbulence, agitation and disturbance and there must be effective means of retarding or slowing up one end of the fiber particularly as it approaches the screen 12 and more particularly the slot 13. In Fig. 6 there is illustrated diagrammatically the general operation and action of the fibers as they move around the screen and inside tank 2.

It has previously been described that the introduction of the unscreened fibers and water through nozzle 6 causes them to travel around the tank until they reach the top of gate 8 when they would overflow and pass from the tank. However, due to the fact that there are openings 13 in the screen 12 there is a tendency for the water of the mixture to flow through the screen openings 13 and if possible to carry with it some of the fibers. These fibers and water which pass through the screen openings 13 and into the space between the screen 12 and the tube 15 are allowed to overflow from this space through openings 44 in the tube 15 and after passing through said openings flow downward through the tube and out through the bottom at 45. These openings 44 are at a somewhat lower level than the upper part of the gate 8, this difference in level being indicated at 46 for that inside the screen and 40 for the level outside of the screen or in the tank 2.

This difference in level establishes a pressure head on the screen, this head being determined by the height of gate 8 which height is adjustable. This pressure head induces a flow of the water or the liquid with which the fibers are admixed through the screen 12 thus drawing the fibers towards the screen as the mixture circulates or passes in a circular path around said screen.

This flow through the screen naturally causes the fibers 42 and 43 to be brought into close proximity therewith and if the fiber is not aligned with the screen as it approaches it and one end touches the surface of the screen 12 before the other the end that first touches will be retarded and those fibers will tend to straighten themselves out as illustrated in the right hand portion of Fig. 6. This condition obtains regardless of the motion of the screening surface and the function of which is described more in detail.

It has already been described how the screen 12 has imparted to it a circular motion, this being controlled and operated by the eccentric 28 operating through lever 18 and link 21. Considering a fragmentary and somewhat diagrammatic view as shown in Fig. 6 the outer tank wall is shown at 2, the screen in one position by full lines designated 12 and in another position shown in dotted lines at 12a, this position being the one the screen would take after the eccentric 28 had made a half revolution from the screen position indicated by the full lines. This circular motion is indicated diagrammatically by the circle 47, the arrow within that circle indicating the direction of motion.

This circular motion can for purposes of illustration be considered as consisting of four separate movements each being substantially in a straight line. These four motions are indicated by arrows placed about the circle 47, the arrows being designated 48, 49, 50 and 51. It will of course be understood that the screen motion will not be in absolutely a straight line as indicated

by these arrows, but for all practical purposes it may be so considered.

It has already been described how circulation of the fibers about the screen 12 cause these fibers to in general arrange themselves parallel to the openings or slots 13 in the screen. It has also been described that due to the fact that the height or level of the pulp mixture outside of the screen is higher than that level on the inside, a pressure head is established which induces a flow through the screen openings 13 to the inside of the screen.

As a fiber particle approaches the screen having naturally been aligned parallel with the screen opening it must be tested or measured as to size to determine whether or not it should or should not pass through the opening 13. The fiber particles in Fig. 6 are shown for purposes of illustration as large oblong particles and thin long particles, the thin ones being such size as should pass through the slots and the others of such size that they should not.

Considering that these fiber particles the larger as 42 and the smaller as 43, have been brought into proximity with the screen surface and are ready to be measured. At this time screen 12 can be considered as about to start moving in the direction of arrow 48. It will be observed that this motion is opposite to the general direction of circulation about the screen, and this motion of the screen in the direction of the arrow 48 further effects or completes paralleling of the fiber particles with the screen openings by contacting the trailing end of the fiber.

When the motion 48 has been completed the next motion of the screen is in direction 49 or for all practical purposes directly towards the previously aligned fiber. The screen moving from the full line position indicated at 12 to the dotted line position at 12a. This motion of the screen in the direction of arrow 49 momentarily increases the pressure head on this part of the screen and accentuates the flow through the screen opening. The large fiber particle 42 and the smaller fiber particle 43 are thus urged against the screen surface and against the slot opening 13 and tend to pass through this opening. The smaller particle can be assumed to be of such size that it will pass through the slot 13 in which case, it will move inside the screen and appear at some point such as 43a. The larger fiber particle, however, can be assumed to be too large to pass through the slot 13 under which condition the screen by its motion in direction of arrow 49 will push this larger fiber particle outward to a position approximately 42a. Thus has screening or fiber-separation been accomplished by a measurement of fiber width or its smaller diameter with a minimum possibility that the fiber, during movement, was lying at an angle or crosswise of the slot opening 13.

The screen motion heretofore described and indicated by the direction of the arrows 48 and 49 occurs during a half revolution of the eccentric 28. The remaining half revolution causes the screen first to move in the general direction of arrow 50 and finally in the general direction of arrow 51 or back to the starting point. The motion 50 is relatively unimportant but the inward motion in direction of arrow 51 accomplishes a very useful purpose.

It will be understood that there is a mass of fibers and water inside the screen and another mass of fibers and water outside the screen. When the screen moved outwardly in the direc-

tion of arrow 49, the natural inward tendency flow was increased due to the water and fiber mass both inside and outside the screen resisting movement. Similarly, when the screen is moved in direction of arrow 51, the water and fiber mass inside the screen 12 resists being moved in this direction resulting in a brief reversal of flow through the screen slots.

This reversal dislodges any fiber particle which may have partly entered slot 13 but which is slightly too large to pass entirely through. The fiber, if left lodged in the slot, would interfere with other fibers from passing through and thus decrease the screen capacity. The short but effective reversal of flow through the screen slot by the screen motion in direction of arrow 51 dislodges such a fiber, leaving the slot 13 available to measure additional fibers.

It will be understood that the screen motion is relatively rapid and the motions as heretofore described and illustrated by the four arrows occur in rapid succession. This means that a portion of the screen surface is being utilized to complete the straightening out of the fibers parallel to the screen slots, a larger portion of the surface is being used to measure fiber particle size when the screen moves in the direction of arrow 49 and a very small portion of the screen has its flow reversed in order to dislodge any fibers which may be partly wedged in any of the slots 13. It will thus be observed that all portions of the screen surface are performing some useful function, these functions in reality traveling about the screen circumference with considerable rapidity.

In practice, it will be found that some of the smaller fiber particles become entangled with the larger ones preventing effective and complete separation. As has already been described, a water pressure chamber 9 and a plurality of nozzles 10 are located in the tank wall 2 opposite the screen 12.

A section through one of these nozzles is indicated in Fig. 8 with a somewhat diagrammatic representation of large and small fiber particles between the tank 2 and the screen 12, these circulating around the tank and screen in the direction of the arrow. At the right hand portion of Fig. 8 there is indicated a mixture of large fiber particles 42 which can be assumed to be entangled with each other requiring some additional means for separating them from each other.

As these fibers circulate around the tank, they pass a plurality of nozzles 10 through which is being forced, under pressure, water or other liquid as indicated by the arrows and lines at the outlet of nozzle 10 in Fig. 8. These jets impinge on the circulating mass of fibers and water as they pass around the tank breaking up any tendency for the fibers to entangle with each other so that the smaller particles can gravitate towards the screen, the larger particles away from the screen or towards the tank wall 2. The result of the disentanglement is illustrated at the left hand portion of Fig. 8.

It is further to be noted that the jets are pointed in the general direction that the fiber mixture is circulating about the tank and the flow through these nozzles aids in maintaining circulation of the mixture around the tank as it spirals upward from the inlet nozzle 6 to the top of the tank and over the gate 8.

It will thus be seen that as the mixture of large and small fibers enter the tank 2 through

nozzle 6 and fill the tank 2 to the top of the overflow gate 8 a head is established on the openings 13 in the screen 12 causing a flow through these openings and out of the screen through openings 44 and tube 15.

The mixture during its travel around the tank as previously described has its fibers aligned with the screen openings, and due to the motion and action of the screen, these fibers are either passed through the screen openings, or rebuffed therefrom and continue to circulate until they reach the top of the gate 8 when they flow over this gate and out through box 7 and pipe 41, such fibers being rejected as unfit for the purpose intended.

During their travel around and around the screen they pass a plurality of washing jets 9, which jets wash out any small acceptable fibers from their possible entanglement with the larger ones, bringing them to the screen surface where they can be tested for proper size, and either passed through the screen openings or rejected therefrom.

The satisfactory fibers are thus thoroughly separated from the unacceptable fibers, the acceptable ones flowing out through tube 15 at 45, and the unacceptable ones flowing over the gate 8 and out through pipe 41. The incoming liquid is introduced in amounts sufficient to maintain the original consistency of the introduced mixture, thereby maintaining the proper ratio of liquid to fiber on the outside of the screen, despite the fact that liquid is being discharged through the overflows at the top of the tank and in the hollow tube 15.

While the device heretofore described is particularly designed and adapted for the screening or separation according to their width or minimum dimension, this shall not be construed as limiting its use to the screening of particles having greater length and width.

In the screening of material where the measurement of particle width is unimportant or where particles may be round or of uniform general dimensions either slotted plates or screen plates with round or square holes may be utilized.

Having thus described my invention what I claim is—

1. An apparatus for classifying fibers comprising an upright, substantially cylindrical tank, a slotted screen within said tank having closed bottom and top sections, the axis of said screen extending in the same general direction as the axis of the tank, a hollow tube supporting the bottom section, screen and top section, means providing overflow holes in said tube above the screening area and a vent pipe in the top of said screen.

2. An apparatus for classifying fibers comprising an upright, substantially cylindrical open top tank, a tangential inlet near the bottom and an overflow box near the top, a plurality of washing jets on one side and a non-rotating cylindrical screen disposed within said tank and means to move said screen bodily relative to said tank, through an orbital path.

3. An apparatus for classifying fibers comprising a tank, a screen within said tank, fixed means to introduce liquid and to establish circulation thereof in said tank, means to impart a circular non-rotating motion to said screen, an overflow means outside of the screen in said tank, effective to establish liquid level within the tank, and overflow means inside of the screen

above the perforations in the screen, providing an outlet for the tank.

4. An apparatus for classifying fibers comprising an upright, substantially cylindrical screen having elongated perforations therein, a tank surrounding said screen, a tangential inlet in said tank for the introduction of the mixture to be classified, means including said inlet to induce a circulation of the incoming mixture within the walls of said tank and about said screen in substantial parallelism with the lengthwise dimension of the elongated perforations whereby the fibers of the mixture are brought into alignment with the elongated perforations, and means to move said screen to effect further fiber alignment with the elongated perforations.

5. An apparatus for classifying fibers comprising a substantially cylindrical open top tank, a tangential inlet near the bottom, an overflow box near the top, a non-rotating, substantially cylindrical screen within said tank positioned with its axis extending in the same general direction as the axis of the tank, a hollow supporting tube within said screen and a movable lever secured to said tube, effective to move said screen and tube bodily relative to said tank.

6. An apparatus for classifying fibers, comprising a substantially cylindrical open top tank, a tangential inlet near the bottom, an open overflow box near the top, a non-rotating, substantially cylindrical screen within said tank positioned with its axis extending in the same general direction as the axis of the tank, a hollow supporting tube within said screen, a movable lever secured to said tube, effective to move said screen and tube bodily relative to said tank, and means to support said lever for movement normal to the axis of the screen.

7. An apparatus for classifying fibers, comprising a substantially cylindrical open top tank, a non-rotating, substantially cylindrical screen within said tank positioned with its axis extending in the same general direction as the axis of the tank, a hollow supporting tube within said screen, a lever secured to said tube, effective to move said screen and tube bodily relative to said tank, a link having one end pivoted to said lever midway of its extremities, and pivotal support means for the opposite end of said link.

8. An apparatus for classifying fibers, comprising a substantially cylindrical open top tank, a non-rotating, substantially cylindrical screen within said tank positioned with its axis extending in the same general direction as the axis of the tank, a hollow supporting tube within said screen, a movable lever secured to said tube, effective to move said screen and tube bodily relative to said tank, said lever being pivoted midway of its extremities, and means to impart a circular motion to said tube and screen thru said lever.

9. An apparatus for classifying fibers comprising a substantially cylindrical tank with an open top, a non-rotating screen within said tank positioned with its axis extending in the same general direction as the axis of the tank, said screen having closed ends, means to maintain a level of stock above said screen in said tank; means to maintain a predetermined level of stock above screen openings inside of said screen and means to remove stock from inside of said screen when it has reached said predetermined level.

10. The method of classifying fibers which comprises introducing said fibers in a fluid mixture at the bottom of a vertically disposed

substantially cylindrical tank having therein a substantially cylindrical screen, imparting a circulatory rotary motion to said mixture within said tank and outside of said screen, periodically washing said fibers as they circulate about said tank, imparting a circular but non-rotating motion to said screen, removing from the outside of the screen such fibers as will not pass through and removing from the inside of said screen, such fibers as do pass through.

11. An apparatus for classifying fibers, comprising a tank, a screen within said tank having elongated perforations therein, an inlet for the unscreened mixture to be classified near the bottom of said tank; means to impart a circular non-rotating motion to said screen whereby the fibers are aligned to said screen openings and means, including the stock inlet and washing jets spaced from said inlet, for insuring a circulatory movement of the unscreened stock about said screen.

12. An apparatus for classifying fibers comprising an upright, substantially cylindrical tank, a substantially cylindrical screen with closed top and bottom sections within said tank, the axis of said screen extending in the same general direction as the axis of the tank, a hollow tube supporting said screen with its closed top and bottom sections, means providing an overflow opening from the interior of the screen to the interior of the tube, and means to move said screen and tube bodily relative to said tank with a non-rotary orbital movement.

13. An apparatus for classifying fibers comprising an upright, substantially cylindrical tank, a slotted screen within said tank having closed bottom and top sections, the axis of said screen extending in the same general direction as the axis of the tank, a hollow tube supporting the bottom section, screen and top section, means providing overflow holes in said tube above the screening area, a vent pipe in the top of said screen, and means to move said screen and tube bodily relative to said tank with a non-rotary orbital movement.

14. An apparatus for classifying fibers comprising an upright, substantially cylindrical tank, a slotted screen within said tank having closed bottom and top sections, the axis of said screen extending in the same general direction as the axis of the tank, a hollow tube supporting the bottom section, screen and top section, means providing overflow holes in said tube above the screening area, a vent pipe in the top of said screen, means to introduce a liquid to be screened into said tank, and means including said supporting tube to mount said screen in complete submergence within the introduced liquid.

15. An apparatus for classifying fibers comprising a tank, a screen within said tank, fixed means to introduce liquid and to establish circulation thereof in said tank, means to impart a circular non-rotating motion to said screen, an overflow means outside of the screen in said tank, effective to establish liquid level within the tank, and overflow means inside of the screen above the perforations in the screen, providing an outlet for the tank, and means including said first overflow means to completely submerge the screen within the tank.

16. An apparatus for classifying fibers comprising an upright, substantially cylindrical screen having elongated perforations therein, a tank surrounding said screen, a tangential inlet in said tank for the introduction of a mixture

to be classified, means including said inlet to induce a circulation of the incoming mixture within the walls of said tank and about said screen in substantial parallelism with the lengthwise dimension of the elongated perforations whereby the fibers of the mixture are brought into alignment with the elongated perforations, means to move said screen to effect further fiber alignment with the elongated perforations, and means to mount said screen in complete submergence within the introduced mixture.

17. An apparatus for classifying fibers comprising a substantially cylindrical open top tank, a tangential inlet near the bottom, an overflow box near the top, a non-rotating, substantially cylindrical screen within said tank positioned with its axis extending in the same general direction as the axis of the tank, a hollow supporting tube within said screen, a movable lever secured to said tube, effective to move said screen and tube bodily relative to said tank, means to introduce a liquid to be screened into said tank, and means including said supporting tube to mount said screen in complete submergence within the introduced liquid.

18. An apparatus for classifying fibers, comprising a substantially cylindrical open top tank, a tangential inlet near the bottom, an open overflow box near the top, a non-rotating, substantially cylindrical screen within said tank positioned with its axis extending in the same general direction as the axis of the tank, a hollow supporting tube within said screen, a movable lever secured to said tube effective to move said screen and tube bodily relative to said tank, means to support said lever for horizontal movement, means to introduce a liquid to be screened into said tank, and means including said supporting tube to mount said screen in complete submergence within the introduced liquid.

19. The method of screening and classifying fibers which comprises confining the fibers in a liquid mixture between a wall of a tank and a screening surface in the tank, circulating the confined mixture about the screen to align fiber particles relative to the screen openings, and to produce a centrifuging action effective to remove unacceptable fibers from the screen, moving the screen in a direction such that a segment thereof moves through a path opposed to the circulating movement of the mixture to create a head on the screen surface and to facilitate passage of acceptable fibers therethrough, and thereafter moving the screen in the same direction as the circulating movement to effect a reversal of flow through the screen openings, and washing the fibers thoroughly during the circulation of the confined mixture.

20. The method of screening and classifying fibers which comprises confining the fibers in a liquid mixture between a wall of a tank and a screening surface in the tank, submerging the screening surface within said confined mixture to eliminate air, circulating the confined mixture about said screen to align fiber particles relative to the screen openings, and to produce a centrifuging action effective to remove unacceptable fibers from the screen, moving the screen in a direction such that a segment thereof moves through a path opposed to the circulating movement of the mixture to create a head on the screen surface and to facilitate passage of acceptable fibers therethrough, thereafter moving the screen in the same direction as the circulating movement to effect a reversal of flow through

the screen openings, and washing the fibers thoroughly during the circulation of the confined mixture.

21. An apparatus for screening and classifying fibers, comprising means to confine a liquid, fiber mixture, between a wall of a tank and a screening means in the tank, said screening means within said confining means, means to circulate a mixture confined in said confining means about said screen to align fiber particles relative to the screen openings and to produce a centrifuging action effective to remove unacceptable fibers from the screen, means to move said screen first, in a direction such that a segment thereof moves through a path opposed to the circulating movement of the mixture to create a head on the screen surface, and to facilitate passage of acceptable fibers therethrough, and thereafter in the direction of circulation to effect a reversal of flow through the screen openings, and means 20 to wash the fibers thoroughly during the circulation of the confined mixture.

22. An apparatus for screening and classifying fibers, comprising means to confine a liquid, fiber mixture, between a wall of a tank and a screening means in the tank, said screening means being positioned within said confining means completely below the normal level of liquid mixture, whereby to eliminate air during a screening operation, means to circulate a mixture confined in said confining means about said screen to align fiber particles relative to the screen openings and to produce a centrifuging action effective to remove unacceptable fibers from the screen, means to move said screen first, in a direction such that a segment thereof moves through a path opposed to the circulating movement of the mixture to create a head on the screen surface and to facilitate passage of acceptable fibers therethrough, and thereafter in the direction of circulation to effect a reversal of flow through the screen openings, and means to wash the fibers thoroughly during the circulation of the confined mixture.

MERLE P. CHAPLIN.
